UNITED STATES PATENT OFFICE

AUGUST W. BEBBER, OF HOUSTON, TEXAS.

STEAM-GENERATING SYSTEM.

No. 893,699.

Specification of Letters Patent.

Patented July 21, 1908.

Application filed October 30, 1907. Serial No. 399,838.

To all whom it may concern:

Be it known that I, AUGUST W. BEBBER, a citizen of the United States, residing at Houston, in the county of Harris and State of

5 Texas, have invented a new and useful Steam-Generating System, of which the following is a specification.

It is a well known fact that the higher the pressure of steam in a boiler, the higher is the 10 temperature thereof. For instance, starting with no pressure and a temperature of 212 degrees F., the boiling point, the temperature at 300 pound pressure is 421.83 F. From this, it will be evident that steam at 15 high pressure may be employed from a single boiler to generate steam at a lower pressure in a number of boilers, and the primary object of the present invention is to provide 20 novel, simple and practicable mechanism for thus generating steam.

The preferred embodiment of the invention is illustrated in the accompanying drawings, wherein:

Figure 1 is an end elevation of the system. 25 Fig. 2 is a side elevation of one of the steam heaters for a secondary boiler, the shell of such boiler being indicated in dotted lines. Fig. 3 is an end elevation of the upper head of the steam heater. Fig. 4 is a cross sectional view through the heater.

Similar reference numerals designate corresponding parts in all the figures of the drawings.

In the embodiment illustrated, the primary boiler is designated 5 and may be of any well known or desired construction, being provided with a suitable furnace 6, gage mechanism 7, and a steam dome 8 having a safety valve 9. The secondary boilers, of 35 which there may be any number found practicable, are designated generally by the reference numeral 10. Each of these secondary boilers consists of a shell 11 suitably supported as shown at 12 and having a steam 40 dome 13 from which leads a suitable supply pipe 14. Gage mechanism 15 and a safety valve 16 are provided for each boiler. Within the shell of each secondary boiler is located a steam heater composed of heads 17 45 and 18 and connecting pipes 19. The heads comprise upper and lower horizontal pipes 20 connected by spaced vertical pipes 21. The pipes 19 which are disposed longitudinally within the shell are connected to the vertical

55 pipes 21. The heater, as clearly shown in Fig. 2, is set at an inclination so that the front head is located higher than the rear head.

A steam supply pipe 23 leading from the dome 8 of the primary boiler, has a suitable 60 controlling valve 24 therein and branches 25, leading from this supply pipe 23, extend through the front end of the different shells 11 of the secondary boilers and are coupled to the lowermost horizontal pipes 20 of the 65 front or higher heads of the steam heaters. Suitable valves 26 are located in the branches 25. A blow off pipe 27 for each heater is connected to the bottom of the rear or lower head, and extends at an inclination downwardly and forwardly through the front end of the shell, being provided with a suitable 70 controlling valve 28. A suitable water feed pipe 29 is provided for each boiler and has a controlling valve 30. The water line is indicated at 31.

With this construction, high pressure steam can be generated in the primary boiler 5 and supplied to different secondary boilers 10, as heating medium therefor. This heating medium serves to raise steam in the boilers 10, as will be evident. The result is a 80 system whereby steam can be generated for a number of plants with great economy and without the necessity of a furnace at each 85 steam generator.

From the foregoing it is thought that the construction, operation and many advantages of the herein described invention will be apparent to those skilled in the art without further description, and it will be understood that various changes in the size, shape, proportion, and minor details of construction may be resorted to without departing 90 from the spirit or sacrificing any of the advantages of the invention.

Having thus fully described my invention, what I claim as new, and desire to secure by Letters Patent, is:

In a system of the character set forth, the 100 combination with a primary steam generator, of a secondary steam generator or boiler comprising an elongated tubular water holding shell, a steam heater located in the shell and composed of vertically disposed heads 105 located at different heights and having vertically arranged spaced pipes and parallel pipes connecting the heads and connected to

the vertical pipes of said heads, said parallel pipes extending longitudinally of the shell and being set at an inclination, a steam supply pipe leading from the primary boiler and connected to the lower portion of the upper head of the steam heater, and a blow-off pipe leading from the lower portion of the lower head.

In testimony, that I claim the foregoing as my own, I have hereto affixed my signature in the presence of two witnesses.

AUGUST W. BEBBER.
